ELECTROLYTIC PRODUCTION OF ACETYLENE CARBOXYLIC ACID

Viktor Wolf, Hamburg, Germany

No Drawing. Application July 8, 1954,
Serial No. 442,203

Claims priority, application Germany July 20, 1953

2 Claims. (Cl. 204—79)

This invention relates to the production of acetylene carboxylic acids.

Various processes are already known for the production of acetylene carboxylic acids.

Propiolic acid has, for example, been prepared by converting acetylene with sodium into sodium acetylide and reacting the latter with CO_2 (U. S. specification No. 2,205,885); alternatively acetylene is converted with chlorine into trichlorethylene, the said product is condensed with formaldehyde and hydrochloric acid is split off, propiolic acid being formed from the alpha-chloroacrylic acid ester thus obtained by further splitting off of hydrochloric acid. Furthermore, acetylene has been converted with formaldehyde into propargyl alcohol and the latter has then been oxidised in sulphuric acid solution by means of chromic acid.

Among the hitherto known methods of preparing acetylene dicarboxylic acid, its production from ethylene halide compounds by treatment with alkali-metals and subsequent carbonisation is of subordinate importance. (Gilman, Haubin, J. Amer. Chem. Soc. 67 (1945), 1420.) Similarly, the action of carbon dioxide on acetylene-di-Grignard compounds is out of the question for synthesis on the technical scale (Ruggli, Helv. 3 (1920), 559; Grignard, Lapayre Faki, C. r. 187 (1928), 517). The conventional method at the present time is to remove hydrogen halide from different halogenated succinic acids or maleic or fumaric acids. It is true that by this means a yield of 73–88% is obtained, but the starting materials are not readily available (Perkin, Simonsen, Journ. Chem. Soc. 91 (1907), 816; Abbott, Arnold, Thompson, Organic Syntheses 18 (1938), 3). It therefore had to be considered as a technical advance when Heilbron and collaborators (J. Chem. Soc. 1949, 604) were able to oxidise in sulphide solution, by means of chromic acid, butin-(2)-diol-1,4 which is today available on a large technical scale. However, the yields could not be increased to more than 23% and could only be obtained by addition of an organic solvent (acetone). According to the invention acetylene carboxylic acids are obtained in good yield by the electrolytic oxidation in acid solution of an acetylene alcohol with one or more primary hydroxyl groups, such as butin-(2)-diol-1,4, or butin-(1)-ol-4 or propin-(1)-ol-3. The anode solution can be worked up in manner known per se, for example by extracting with an organic solvent, drying the extract and evaporating the solvent in vacuo. This process is of value from a technical point of view, not only on account of the cheap oxidising means, but also because it can be carried out with inexpensive anode material and with current densities of, for example, up to 10 amps./dm.² without the yields being appreciably reduced. By this means, it is possible to obtain a high transformation per unit of time with electrodes of small dimensions.

According to a preferred embodiment of the present invention, the temperature in the anode space during the oxidation process is kept below 50° C., more preferably below 20° C., for which purpose external cooling may be necessary. When the temperature rises substantially above

2

20° C., for example to 30–40° C., the yield is lowered as compared with the yields which are obtainable by using lower temperatures. Whereas it is possible, for example, under otherwise equal conditions to obtain a yield of about 72% of acetylene dicarboxylic acid when butin-(2)-diol-1,4 is oxidised electrolytically to give the said acetylene dicarboxylic acid, using a temperature range of about 8–9° C., the yield drops to about 58% when the same operation is carried out without cooling and the temperature in the anode space rises to 30–40° C. owing to spontaneous heating. This latter yield is still always substantially better than the yield which can be obtained according to the known processes. In the interest of industrial efficiency, however, it is expedient to determine and observe the optimum reaction temperature in each particular case.

Furthermore, it has been found that it is expedient not to select too high an alcohol concentration and preferably to keep it below 25%. In the case of the oxidation of butin-(2)-diol-1,4 to form acetylene dicarboxylic acid, it was found that an alcohol concentration of about 6% is particularly expedient. Whereas in this special case, under otherwise equal conditions, with an alcohol concentration of about 4–5%, the yield of acetylene dicarboxylic acid amounts to about 72% of the theoretical, the yield with an alcohol concentration of 10–11% drops to about 51%. The yield of 51% is substantially better than that which can be produced with the previously known processes, but it is nevertheless in the interest of the industrial efficiency 30 of the process to determine the optimum alcohol concentration in each particular case.

It is expedient to select sulphuric acid as the acid. The influence of the sulphuric acid concentration on the yield is not very pronounced. It is possible for the sulphuric acid concentration in the anode space to be lowered to about 1% without thereby substantially impairing the yield. On the other hand, it is not desirable to raise the sulphuric acid concentration beyond 30%, because the yield then begins to fall by a few percent.

When carrying out the process of the invention, it is only necessary to cover the anode space and provide it with a reflux condenser when the starting products or intermediate products or end products are readily volatile. It is also not necessary to move the anode liquid with all acetylene alcohols.

45 The current density has an appreciable influence on the yield. For example, in the production of acetylene dicarboxylic acid, it is possible to operate in the range of 1–6 amp./dm.², but the yield of acid drops with higher current densities. When the amount of current theoretically necessary for the formation of acid is varied, more than 70% acid is already obtained with 90% current energy, but the yield drops gradually when the current energy is more than 110%. It is expedient to use lead dioxide anodes. It is also desirable to separate the anode and cathode chambers in a suitable manner.

The present process gives crude products in the form of acids of high concentration, which are not or are only slightly contaminated by by-products, and which may be used as such or if desired may be further worked up into pure end products. In the case of acetylene dicarboxylic acid, a crude product which is 91–95% pure is obtained in the form of a light-yellowish to light-brownish powder. The yields which are obtainable according to the present process are substantially higher, for example in the case of acetylene dicarboxylic acid, than the yields which can be produced by the prior known processes.

Example 1

In a rectangular electrolysis vessel, the anode chamber is separated from the cathode chamber by a clay plate as diaphragm. Plate glass sheets, fitted on by means of a

grease packing, serve to cover the electrode chambers. The plates are drilled above the cathode chamber to carry a reflux condenser through which extends the cable supplying current to a 8 x 16 cm. copper plate anode, while a second reflux condenser is arranged above the anode chamber, the stem of a mechanically operated agitator extending through a latter condenser. The two ends of an 8 x 10 mm. lead tube serving as anode also project through the cover of the anode chamber. The lead tube is immersed over a length of 63.5 cm., laid in flat convolutions, i. e. with an effective surface of 1.0 dm.², in the anode liquid. 50 gm. of 96% propargyl alcohol and 550 gm. of 15% sulphuric acid are disposed in the anode chamber, while the cathode chamber contains 15% sulphuric acid. Water is passed through the reflux condensers and the anode, so that a temperature of 8.5-9° C. is maintained in the anode chamber during the electrolysis. While constantly stirring, a current of 4.0 amps. with a terminal voltage of 3.2 volts is passed through for 26.9 hours, this corresponding to 107.6 ampere hours=112.5% of the theoretical current energy. After a few minutes, the lead anode is covered with a blackish-brown oxide layer. While at the outset only traces of gas appear in the anode chamber, the evolution of gaseous oxygen slowly increases towards the end of the electrolysis. The anode liquid, which has then become turbid and light-yellow, is filtered, salted out by addition of common salt and extracted for 22 hours at room temperature with ether. The yellow extract is dried over calcium chloride and the ether is completely distilled off from the boiling water bath. The residue is distilled under the vacuum of a water pump on an initially warm and then boiling water bath and produces 53.25 gm. of a light yellow clear liquid which contains 89.35% of propionic acid, i. e. 47.6 gm. of a 160% acid=76.1% of the theoretical. The current yield is 67.5%.

Example 2

In a rectangular electrolysis vessel, the anode chamber is separated from the cathode chamber by a clay plate as diaphragm. The cathode is a copper plate of 8 x 16 cm., which dips into approximately 15% sulphuric acid. The anode is a lead tube of 8 x 10 mm. which is coated by a dioxide layer and is immersed over a length of 63.5 cm., laid in flat convolutions, i. e. with an effective surface of 1.0 dm.², in the anode liquid. The anode chamber contains 25 gm. of pure, butindiol, dissolved in 510 gm. of water, and 90 gm. of concentrated sulphuric acid. Water flows through the anode, so that a temperature of 8-9° C. is maintained in the anode chamber during the electrolysis. A current of 3.0 amps. with a terminal voltage of 3-4 volts is passed through for 26 hours and 36 minutes, which corresponds to 79.75 ampere hours=110% of the theoretical current energy. Towards the end of the electrolysis, the evolution of gaseous oxygen increases. The anode liquid is filtered, salted out by addition of common salt and extracted for 8 hours with ether. The extract is dried over calcium chloride, filtered off from the latter and the solvent distilled off in vacuo. There remain 25.75 gm. of a light brown powder with an acid content of 94.75%, i. e. 24.4 gm. of a 100% acid=73.9% of the theoretical. The crude product melts at 169-174° C. with decomposition.

Example 3

The operation is carried out as in Example 2, but instead of the quantities of 25 gm. of pure butindiol, 510 gm. of water and 90 gm. of concentrated sulphuric acid, as indicated in Example 2, there are now introduced 10 gm. of hexan-diene-(2,4)-diol-1,6 in 500 gm. of 3% sulphuric acid. The apparatus is encased in black paper. A current of 1.0 amp.=0.01 amp./cm.² current density is used. The current is passed through for 19.5 hours, which corresponds to 100% of the theoretical current energy. The anode liquid is extracted for 5 hours with ether. The material extracted is cooled with water, whereupon it becomes darker. The extract is washed twice with a little water. It is then dried over calcium chloride, a low temperature being ensured by storing in a refrigerator. The red filtrate is mixed with 5 times the quantity of petroleum ether, decanted from the precipitated polymer and again diluted with petroleum ether to 5 times the volume. In the refrigerator, the acid crystallises into initially pure white crystals, which are discoloured to greyish-red crystals in spite of cooling and darkness. The yield is 1.333 gm. of diacetylene dicarboxylic acid in the form of the dihydrate and in fact the crude yield has a content of 96.8% of dihydrate. The yield therefore corresponds to 1.29 gm. of 100% dihydrate=8.15% of the theoretical.

The crystals darken at 95-100° C. and decompose without explosion.

From the filtrate, there is obtained, after strong concentration and precipitation with petroleum ether, a further 0.531 gm. of a 91% dihydrate=0.483 gm. of 100% dihydrate=3.05% of the theoretical.

What I claim is:

1. A method of producing acetylene carboxylic acids, comprising the steps of subjecting an acetylene alcohol in a sulfuric acid solution containing a maximum of 30% sulphuric acid to electrolytic oxidation at a current density of up to 10 amps./dm.² in an electrolytic cell supplied with lead dioxide anodes and having separate anode and cathode compartments and at a temperature of below 20° C., the concentration of said acetylene alcohol in said acid solution being between 4-25%, thereby converting said acetylene alcohol to the corresponding acetylene carboxylic acid; and recovering said acetylene carboxylic acid.

2. A method of producing acetylene carboxylic acids, comprising the steps of subjecting butin-(2)-diol-1,4 in a sulfuric acid solution containing a maximum of 30% sulphuric acid to electrolytic oxidation at a current density of up to 10 amps./dm.² in an electrolytic cell supplied with lead dioxide anodes and having separate anode and cathode compartments and at a temperature of below 20° C., the concentration of said butin-(2)-diol-1,4 in said acid solution being between 4-25%, thereby converting said butin-(2)-diol-1,4 to the corresponding acetylene carboxylic acid; and recovering said acetylene carboxylic acid.
